CLAIM

The ornamental design for a leaf rake head, substantially as shown and described.

DESCRIPTION

FIG. 1 is a top plan view of a leaf rake head embodying our new design;

FIG. 2 is a bottom plan view thereof;

FIG. 3 is a side elevation thereof which is a mirror image of its laterally opposite side; and

FIG. 4 is a rear elevation view thereof.

FIG. 1

FIG. 2

FIG. 3

FIG. 4
